APPARATUS FOR SEPARATING
GALVANIZED ARTICLESEdward M. Skipper, Baltimore, Md., assignor to
Locke Insulator Corporation, Baltimore, Md., a
corporation of Maryland

Application August 8, 1942, Serial No. 454,177

3 Claims. (Cl. 91—59.3)

My invention relates to an apparatus for separating galvanized articles and its principal object is to produce simple and reliable means into which comparatively small articles such, for example, as washers may be discharged after being removed from a galvanizing bath so that such of the articles which have adhered to each other may be readily separated.

A primary feature of the invention consists in providing a housing in which is rotatably mounted a substantially horizontal plate, the periphery of the plate being spaced from the sides of the housing so that articles dropped into the latter may fall to the bottom thereof and means being disposed above the plate and rotatable therewith for striking articles dropped into the housing and projecting them toward the sides thereof.

Another feature of the invention consists in providing the horizontal plate which is rotatably mounted in the housing with a plurality of radial arms which project beyond the periphery of the plate.

Still another feature of the invention consists in providing an upright substantially cylindrical housing with a plurality of vertically spaced rotatable plates, the outer edges of said plates being spaced from the side walls of the housing to provide openings through which articles dropped into the housing may fall to the bottom thereof and the top one of said plates being rigidly provided with radial arms for striking articles dropped into the housing and projecting them toward the sides thereof.

Other and more specific features of the invention, residing in advantageous forms, combinations and relations of parts, will hereinafter appear and be pointed out in the claims.

In the drawing,

Figure 1 is a vertical sectional view of the apparatus.

Figure 2 is a horizontal sectional view taken on line 2—2 of Figure 1.

Figure 3 is a horizontal sectional view taken on line 3—3 of Figure 1.

Referring more particularly to the drawing, 1 indicates the housing of the apparatus which is preferably of substantially cylindrical shape in cross section. The upper portion of the housing is provided with an overhanging hood or shield 2 which may, if desired, be formed integral therewith and it defines an opening 3 through which galvanized articles may be dropped into the housing. The opening is of such size and shape that the wire baskets, in which articles are custom-

arily placed while being galvanized, may be readily inserted therein and sufficiently tilted to discharge their contents into the housing.

5 Rotatably mounted within the housing on an axis concentric therewith are a plurality of circular plates 4 and 5 respectively. The plates are vertically spaced and are preferably arranged horizontally. They are both keyed or otherwise suitably made rigid with a vertical shaft 6 which is journaled in bearings 7 and 8, each of which is rigidly supported by arms 9 connected in any suitable manner to the side walls of the housing. Just below the upper plate 4, the shaft is 10 preferably formed with a thrust collar 10 which cooperates with bearing 7.

The periphery of each of the plates 4 and 5 is spaced from the side walls of the housing to provide openings of sufficient size to permit articles dropped into the housing to fall to the bottom thereof. Disposed above the upper plate 4 and preferably made rigid therewith are a plurality of radial arms 11 which, in addition to projecting above the upper surface of the plate, extend beyond the outer edge thereof to points 15 closely adjacent the side walls of the housing. Shaft 6 may be rotated by any suitable means such, for example, as an electric motor 12 which may be mounted directly on the housing. Rather than connect the motor shaft 13 to the vertical 20 shaft 6 by gearing, a universal joint 14 between these two shafts will be found sufficient and, in order that the motor shaft will not interfere with inserting the wire baskets used in galvanizing the articles into the housing, the motor shaft is 25 arranged at a substantial angle to the vertical and extends into the housing on the side opposite the opening 3.

With the shaft 6 being rotated at a speed of 30 approximately 400 revolutions per minute, it will be readily appreciated that articles which are dropped into the housing will be struck with considerable force by the radial arms 11 and projected against the sides of the housing. They will then fall downwardly between the outer edge 35 of the upper plate 4 and the housing. Some may fall all the way to the bottom of the housing, passing between the outer edge of the lower plate 5 and the side walls of the housing, while others by hitting against the housing or the supporting arms 9 of bearing 7 will be deflected and fall upon the lower plate. Such of the articles as fall on the lower plate will be immediately thrown outwardly toward the walls of the housing because like the upper plate it is also 40 rotating rapidly. All the articles dropped into 45

the machine will, therefore, be violently struck one or more times and such of them as may have become stuck together during the galvanizing operation will be readily separated.

In the bottom of the housing is a pan or box 15 into which the separated articles fall. Water is preferably kept in the pan so that, if the galvanized articles are introduced into the housing while they are still hot, they will be cooled by the water and thus prevented from again sticking together after once being separated. The pan may be removed from the housing through an opening, not shown, in the base thereof which, if desired, may be advantageously formed as a separate member 16 having at its 15 lower edge an outwardly extending marginal flange 17.

From the foregoing, it will be perceived that I have devised a simple and reliable apparatus for separating galvanized articles. Various modifications may, of course, be made in detail features of construction without departing from the spirit of the invention as defined in the appended claims.

What I claim is:

1. In a machine of the class described, the combination of a housing, a substantially horizontal plate member rotatably mounted in said housing and having its periphery spaced from the inner wall of the housing to provide a space 30 through which articles dropped into the upper portion of the housing may fall to the bottom thereof, and means disposed above said plate and rotatable therewith for striking articles dropped into the housing and projecting them toward the 35

sides thereof, said means extending outwardly of the marginal edge of said plate member.

2. In a machine of the class described, the combination of a housing of substantially cylindrical shape in cross section, a circular plate mounted within said housing and rotatable about an axis concentric therewith, the periphery of said plate being spaced from the inner wall of the housing to provide an opening through which articles dropped into the upper portion of the housing may fall to the bottom thereof, and a plurality of radial arms arranged above said plate and rotatable therewith for striking articles dropped into the housing so as to project them toward the sides thereof, the outer ends of said arms extending into the space between the marginal edge of said plate and the adjacent wall of said housing.

3. In a machine of the class described, the combination of an upright substantially cylindrical housing, a substantially horizontal plate mounted within the housing and rotatable about an axis concentric therewith, the outer edge of said plate being spaced from the side inner wall 25 of the housing to provide an opening through which articles dropped into the upper portion of the housing may fall to the bottom thereof, and radially extending arms rigidly mounted on the upper surface of said plate and extending outwardly of the marginal edge thereof for striking articles dropped into the housing and projecting them toward the sides thereof upon the rotation of said arms.

EDWARD M. SKIPPER.
